REGENERATIVE DETECTOR CIRCUIT

Harry E. Thomas, Haddonfield, N. J., assignor to
 Radio Corporation of America, a corporation of
 Delaware

Application December 30, 1942, Serial No. 470,547

7 Claims. (Cl. 250—20)

The present invention relates to a regenerative detector circuit and more particularly to a detector circuit of this type provided with automatically compensated feed-back coupling means and which is capable also of being used efficiently in multi-band receivers.

Because of their simplicity and low cost, radio receivers of the tuned radio frequency type are desirable in certain fields of use. In order to increase the sensitivity and the signal-to-noise ratio of such receivers, it is known to employ a triode, tetrode or a pentode tube as a regenerative detector. Such receivers are frequently employed, depending upon the degree of regeneration, for the reception of code or c. w. (continuous wave) signals or of voice modulated signals. For telegraph reception, sufficient radio frequency energy in the output circuit of the detector is fed back into the grid circuit to produce oscillations which heterodyne with the incoming signal. However, with the detector regenerative, that is, with feed-back taking place but not enough to cause oscillation, voice modulated signals may be received with considerably greater strength than when the detector is in a non-regenerative condition. The sensitivity of the regenerative detector is greatest when the tube is oscillating very weakly, in beat-note reception, or when very near the oscillation point but not actually oscillating, in the reception of telephone or voice signals. In order to obtain the adjustment for greater sensitivity it is customary to provide a regeneration control.

There are various known forms of regenerative detectors but they have certain disadvantages and are not readily adaptable for use in multi-band receivers. For example, in one particular circuit that has been used to some extent and to which reference will be made hereinafter, it is necessary, in switching from one band to another, to switch in the appropriate one of a plurality of feed-back windings. It is necessary also to set the regeneration control for the different frequencies in each band due to changes in the gain and feed-back with frequency. In addition there are spurious responses caused by the feed-back coil resonances and the expense of additional windings and a switch.

It is therefore the main object of my invention to provide an improved regenerative detector circuit which will avoid the above and other disadvantages.

Another object is to provide automatically

compensated coupling in a regenerative detector in order to obtain constant sensitivity over a given frequency band.

Other objects of the invention are to improve generally the simplicity and efficiency of regenerative detectors for use in multi-band receivers.

The novel features characteristic of my invention are set forth with particularity in the appended claims. The invention itself, however, both as to its organization and mode of operation together with further objects and advantages thereof, will best be understood by reference to the following description taken in connection with the accompanying drawing in which

Fig. 1 illustrates a known regenerative detector used in a multi-band receiver, and Fig. 2 is a regenerative detector circuit embodying the present invention.

Referring first to Fig. 1 of the drawing, the receiver of the prior art is shown for illustrative purposes to be a three-band receiver, and to include a preselector system, shown diagrammatically by the block 1, and a regenerative detector circuit which includes the tube 2. The preselector may include one or more radio frequency amplifiers, incoming signals being fed to the input thereof from the antenna 3 or other signal collector. The amplified selected signal frequency appearing in the output 4 of the preselector is transmitted to the signal control grid 5 of the detector tube 2 (which may be a screen grid or a pentode tube) through one of the interstage coupling transformers T₁ to T₃, depending upon the frequency band desired to be received which is determined by the position of the switch members S₁ and S₂. The several primaries 6 to 8 of the coupling transformers have their low potential ends connected to a conductor 9 which through the filter constituted by the resistor 10 and the condenser 11 leads to the +B terminal of a suitable source of power. The high potential ends of the primaries terminate in the switch contacts with which the switch member S₁ is adapted to selectively contact. The transformer secondaries 12 to 14 have their low potential ends connected to the grounded conductor 15, their respective high potential ends terminating in the switch contacts with which the switch member S₂ is adapted to selectively contact. A variable condenser 16 is connected between the grid side of the switch S₂ and ground and forms with any one of the transformer secondaries 12 to 14, as determined by the position

of the band switch, a tunable input circuit for the detector. The usual grid condenser and grid leak resistor for this type of detector are indicated respectively at 17 and 18. The tuning condenser 16 and one or more tuning condensers 19 of the preselector system are controlled in unison, the dotted line connection 20 therebetween representing such uni-control operation.

The regenerative feed-back in the detector circuit above described is obtained by the selective connection to the cathode 21 of the tube of one of a plurality of windings 22 to 24 which are coupled respectively to the secondary or grid windings 12 to 14 in proper phase. The cathode or feed-back windings have their low potential ends connected to a common lead 15 which is grounded, their other ends terminating in contacts with which the switch member S₃ is adapted to selectively contact. The switch members S₁ to S₂ and one or more others that may be included in the preselector are actuated in unison and constitute the band switch which determines by its position of adjustment the particular frequency band being received.

The output 25 of the detector includes a plate load resistor 26 connected between the +B terminal of the power supply and the plate electrode 27, a coupling condenser 28 being connected from the plate side of the load resistor for transmitting the detected signals to the audio amplifier and utilization device, not shown. A variable tap 29 on the potentiometer 30 serves to supply voltage to the screen grid 31. The condenser 32 is a high frequency by-pass condenser for screen grid currents.

Briefly the operation of the regenerative detector is as follows:

With the band switch set in the position shown in the figure to receive signals in the band determined by the transformer T₁, the tuning condenser 16 is adjusted to tune the secondary 12 of said transformer to a desired frequency within the selected band. The signal frequency impressed on the control grid 5 is then rectified by the method known as grid-circuit rectification, the rectified or detected signal in amplified form appearing in the output or plate circuit 25. Radio frequency currents of the signal frequency are also present in the plate and screen grid circuits, and since the cathode coil 22 is included in these circuits, some of the high frequency energy will be fed back to the input circuit due to the coupling between the coils 22 and 12. The regeneration is controlled by adjustment of the tap 29 to vary the screen grid voltage.

As pointed out previously the system above described is subject to the disadvantage that each time the receiver is adjusted to a new frequency, whether in the same or different band, it is necessary to adjust the regeneration control for most efficient operation. For example, if the receiver is tuned anew to a certain signal which happens to be of a different signal strength than that to which the receiver was previously tuned, unless the regeneration control is properly adjusted the detector circuit will regenerate either too weakly or too strongly.

In Fig. 2 of the drawing there is disclosed a regenerative detector circuit according to the invention designed to overcome the above and other disadvantages previously mentioned.

The circuit of Fig. 2 is in many respects like that of Fig. 1, except as noted hereinafter, similar or corresponding elements in both figures being represented by the same reference char-

acter. The cathode or feed-back coils employed in Fig. 1 are omitted in the circuit of Fig. 2. Instead the cathode return is connected by way of the lead 33 to the common lead 15' to which are connected the low potential ends of the several transformer secondaries 12 to 14. Between the lead 33 and ground there is connected a network which comprises a condenser C and an inductance L connected in series. A resistor R is shunted across the series combination of L and C and serves to complete the cathode D. C. path and also to provide grid bias. The above network it will be noted is connected between cathode and ground, and being included in both the grid and plate circuits of the detector tube 7, it serves as the feed-back coupling means between the plate and grid circuits. A variable condenser 34 is mechanically coupled and movable with the tuning condenser 16 and is connected to lead 33 and ground thereby shunting the coupling network C, L and R.

The series combination of L and C is chosen series resonant below the range of tuning of the several bands, so that the effective inductance of this combination becomes less as frequency decreases. This tends to make regeneration inadequate at lower frequencies of the band. However, the capacity 34 becomes greater as the circuit is tuned to lower frequencies, and the effective inductance of the entire network of L, C and 34 can thus cause to decrease, increase, or remain constant with decreasing frequency according to the amount of capacity of 34 at each frequency adjustment. It will be seen that a capacity variation curve for 34 can thus be chosen such that the amount of regeneration will be automatically maintained at an optimum value throughout the range of tuning for any given band.

40 The variable condenser 34 serves therefore to control the regeneration automatically. Except for changes necessary when going from band to band, the regeneration control by adjustment of the tap 29 of the screen voltage is unnecessary 45 since feed-back and regeneration are nearly constant over the individual frequency ranges.

While I have shown and described certain preferred embodiments of the invention, it will be understood by those skilled in the art that modifications and changes may be made without departing from the spirit and scope of the invention.

What I claim is.

1. A regenerative detector comprising an electron discharge tube provided with at least a cathode, a signal control grid and an anode, an input circuit having its inductance connected between signal grid and cathode and its variable capacitor connected between the grid end of the inductance and ground, and a feedback network connected 55 between the cathode end of the inductance and ground.

2. A regenerative detector as defined in claim 1 wherein the feedback network comprises a fixed combination of resistance, capacitance and inductance.

3. A regenerative detector as defined in claim 1 wherein the feedback network comprises a fixed combination of resistance, capacitance and inductance and a variable capacitor adjustable 70 with the variable capacitor of the input circuit connected across the feedback network.

4. A regenerative detector comprising an electron discharge tube provided with at least a cathode, a signal control grid and an anode, a network 75 providing regenerative feedback from the output

to the input circuit of said tube connected between cathode and ground and included in both the grid to cathode and anode to cathode circuits, and a variable capacitor shunted across said feedback network for controlling regeneration.

5. A regenerative detector adapted for use in a multi-band receiver comprising an electron discharge tube provided with at least a cathode, a signal control grid and an anode, a network operating in each of the bands providing regenerative feedback from the output to the input circuit of said tube, said network being connected between cathode and ground and included in both the grid to cathode and anode to cathode circuits, and a variable capacitor shunted across the network for controlling regeneration.

6. A regenerative detector as defined in claim 5

wherein the feedback network comprises a series connected capacitor and inductance which offer a substantially constant impedance to the feedback energy over a wide band of frequencies.

5 7. A regenerative detector comprising an electron discharge tube provided with at least a cathode, a signal control grid and an anode, a resonant input circuit tunable over a range of frequencies connected between said control grid and cathode and including an inductance and a variable capacitor effectively connected in parallel, and a feedback network connected between the cathode end of the inductance and ground and which is included also in the plate to cathode output circuit.

HARRY E. THOMAS.
